UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

SOLE-LEVELING MACHINE.

1,165,768.

Specification of Letters Patent.

Patented Dec. 28, 1915.

Application filed December 7, 1910. Serial No. 596,067.

To all whom it may concern:

Be it known that I, ANDREW EPPLER, a citizen of the United States, residing at Lynn, in the county of Essex and State of Massachusetts, have invented certain new and useful Improvements in Sole-Leveling Machines; and I do hereby declare the following to be a full, clear, and exact description of the invention, such as will enable others skilled in the art to which it appertains to make and use the same.

The present invention relates to sole leveling machines and more particularly to machines of this type which comprise a shoe supporting jack and a coöperating sole leveling device movable to change the relative longitudinal position of the leveling device and jack.

The object of the present invention is to provide certain improvements in a machine of this type which cause the proper leveling action to be exerted over all portions of the shoe sole acted upon by the leveling device, and which impart a better finished appearance to the sole.

With this object in view the several features of the invention consist in certain novel features of construction, combinations and arrangements of parts hereinafter described and claimed, the advantages of which will be obvious to those skilled in the art from the following description.

In the accompanying drawings illustrating the preferred form of the invention, Figure 1 represents a side elevation of the improved leveling machine; Fig. 2 is a top plan view of the leveling machine; Fig. 3 is a side elevation of the leveling machine with the shoe supporting jack and driving mechanism therefor removed; Fig. 4 is a sectional elevation taken upon the line 4—4, of Fig. 1; Fig. 5 is a detail showing the leveling roll with the friction device applied thereto; Fig. 6 is a section upon the line 6—6, of Fig. 5; Fig. 7 is a detail illustrating the mechanism for obtaining an increased pressure of the leveling roll upon the shank portion of the sole.

In the illustrated embodiment of the invention, the leveling roll 1 is journaled in the forward end of a frame 2 which is pivotally mounted at its rear end upon the upper rear portion of the machine frame 4.

The leveling roll 1 is vibrated by an eccentric 5 which is connected to the shaft 6 of 55 the leveling roll through a pair of connecting rods 7 which are connected at their outer ends to opposite ends of the shaft 6 and at their inner ends to two arms of a three-armed bell crank 8, the third arm of the bell 60 crank being connected to the eccentric by a link 9. The ends of the shaft 6 are journaled in slide bearings 10, which enables the shaft and leveling roll to be vibrated by the connecting rods 7. The eccentric 5 is mounted upon a counter shaft 11 which is driven by a pulley 12 and belt 12^a from a pulley 13 mounted upon the main drive shaft 3 of the machine.

The shoe is oscillated mechanically beneath the leveling roll and at the same time is manually tipped by the operator to properly level the edges of the sole. The operating mechanism for oscillating the shoe supporting jack comprises means for reversing 75 the travel of the jack at the will of the operator and means for automatically stopping the movement of the jack in either direction when certain predetermined limits of movement are reached, as for example, when the 80 leveling roll in its rearward movement reaches the front portion of the heel seat. The shoe supporting jack and operating mechanism are substantially the same as shown in the co-pending application of the 85 applicant, Serial No. 315,024, filed May 3, 1906, and this construction is only briefly described herein in consequence thereof. The shoe supporting jack comprises a frame 14 provided with suitable heel and toe supports and pivotally mounted in a jack supporting frame 15, which frame is pivoted 90 at 16 upon the main frame of the machine. The operating mechanism for the jack comprises a triangular frame 18 pivotally 95 mounted upon the shaft 3 and having the pulleys 19 and 20 journaled in the upper portion thereof. These pulleys are located adjacent to the periphery of the large friction pulley 21 and diametrically opposite 100 to one another. The pulleys 19 and 20 are driven by a belt 22 from the drive pulley 23 mounted upon the main drive shaft of the machine. An idler 24 is provided about which the belt passes in order to keep it 105 under tension at all times. Friction disks

19^a and 20^a are mounted upon the shaft of each of the pulleys 19 and 20 respectively and the friction pulley 21 is driven from either of these disks as the frame 18 is swung 5 to bring either disk into engagement with the surface of the friction pulley. Movement is transmitted to the frame 15 upon rotation of the pulley 21, through the gears 27 and 27^a, the crank disk 60 and link 17 connecting the disk and jack frame. The frame 18 is conveniently moved by the operator through a hand lever 25 pivotally mounted upon the shaft 16 journaled in the machine frame and connected to the frame 18 by a link 26. Upon the release of the hand lever the frame is returned to a neutral position by the springs 77 which surround a rod 78 fastened to the frame 18, the rod passing through a hollow lug 79 mounted in the machine frame and against opposite sides of which the springs 77 bear. To prevent an overthrow of the jack supporting frame and to throw the friction driving mechanism out of operation when 20 the jack supporting frame reaches its limit of movement in either direction, the gear 27 is provided at diametrically opposite points with adjustable pins 28 and 29, which pins are arranged to engage an arm 30 pivotally mounted upon the shaft 16. The arm 30 is connected with the frame 18 through links 31 and 32 and springs 33 in order to prevent a shock upon stopping the movement of the jack.

25 The frame 2, in which the leveling roll is mounted, is counterbalanced by a spring 35 which connects the rear end of the frame at 36 with the rear portion of the machine frame 4. The leveling roll is pressed down 30 upon the sole of the shoe by a compression spring 38 which bears against a hollow casting 39 at its upper end and a disk 40 threadedly connected to the rod 41 at its lower end, the rod 41 being connected to the frame 2 through a coupling 42. A stop is provided for limiting the downward movement of the frame 2 comprising a member 43 supported by the frame and contacting with the upper slotted portion of a rod 44.

45 The stop member 43 is threadedly mounted in the stem 45, which is arranged to be rotated through the gears 46 and 47, the worm 48 and worm wheel 49, and the hand wheel 50. A pin 51 is provided for fastening the gear 46 to the stem 45, but may be removed to allow the gear to rotate freely upon the stem. The purpose of this arrangement is to enable the stop to be adjusted and to simultaneously increase or decrease the tension of the spring 38 as clearly illustrated and described in the patent to Rigby, No. 925,509, dated June 22, 1909.

55 It is desired to move the stop member 44 out of the way during the leveling operation in order that the leveling roll may be

pressed down by the spring 38 into the shank portion of the sole without the stop members 43 and 44 engaging with one another. This is accomplished by providing a toggle 52, which is fastened to the lower end of the stop member 44 at its upper end and to the machine frame at its lower end, and which is connected at its middle portion to one end of a tension spring 53. The spring is fastened at its opposite end to the arm 54, and normally tends to break the toggle and slide the member 44 downwardly. A link 55 connects the middle portion of the toggle and the upper end of a lever 56 which is pivoted centrally upon the machine frame and carries a cam roll 57 upon its lower end, the cam roll bearing against the periphery of a cam 58 mounted upon a cam shaft 58^a. The cam 58 is provided with a cam projection 59, adjustably fastened to its periphery and which is arranged to contact with the cam roll 57 and straighten the toggle in order to maintain the leveling roll in a raised position when the roll is out of engagement with the shoe. The leveling roll is held in this position until the shoe is again moved into engagement with it, when the cam roll 57 again rides off the cam projection 59, allowing the toggle 52 to be broken by the spring 53, lowering the stop member 44 and allowing the leveling roll 1 to properly follow the contour of the sole and level the shank.

In various classes of shoes, and more particularly in that class of shoes having what are known as cottage shanks, it is particularly difficult to properly level the shank, and in such cases it is deemed advisable to increase the pressure of the leveling roll upon the sole at the shank. In the present invention, the machine is enabled to operate at the best efficiency upon varying styles of shoes by mechanism which is connected to the roll to increase the pressure upon the shank and which has provision for an adjustment to vary the application of the pressure. It is preferred to accomplish this result by providing a cam disk 60 mounted upon the shaft 58^a, the cam disk being provided with a circumferentially adjustable projection or cam rib 61 adapted to engage with a cam roll 62, journaled upon the middle portion of the lever 63 which is pivoted in the machine frame at 64 and connected at its free end to the lower portion of the casting 39. It can readily be seen that when the projection 61 engages with the cam roll 62, the rod 63 and casting 39 will be forced downwardly, increasing the compression upon the spring 38 and consequently the pressure which the leveling roll 1 will exert upon the sole. The cam projection 61 is so arranged that it will engage the roll 62 when the leveling roll 1 is in engagement with the shank portion of the sole.

It has been found desirable in operating upon certain classes of welt shoes to have the leveling roll exert a rubbing action upon the sole, which imparts a more finished appearance to the sole and gives it a slight burnish. In the present invention, this is accomplished by frictionally retarding the free rotation of the roll in order to cause it to slide over the surface of the sole. Means are also provided under the control of the operator for varying the retardation of the roll in order to adapt the machine for successful operation upon various classes of work in which different degrees of rubbing action are required. To this end, a friction device is provided comprising a brake 65 which is lined with any preferred form of friction material 66, and is pressed downwardly against the upper portion of the roll by a spring 67 surrounding a rod 68, which projects upwardly from the brake into the hub of a hand wheel 69. The hand wheel 69 has its hub threadedly mounted in a bridge piece 70 and a rotation of the hand wheel will increase or diminish the pressure of the spring 67 upon the brake 65. The bridge piece 70 has its threaded portion split and clamped together by the bolt 71 in order to retain the hand wheel 69 in any adjusted position. In order that the brake 65 shall move with the leveling roll, the bridge piece is supported upon a pair of arms 72 projecting upwardly from the slide bearings 10.

It is desirable that the operator, at certain times during the leveling operation be able to raise the leveling roll from the sole of the shoe in order to either examine the shoe or to decrease the pressure upon that portion of the sole. To enable the leveling roll to be raised the rear end of the frame 2 is connected with a treadle 73 by the connecting rods 74 and 75, the connecting rods being fastened at their point of connection to an arm 76 pivoted upon the rod 77. A spring 78 is provided which connects the treadle 73 with the frame of the machine and tends to raise the treadle and allow the leveling roll to return to its normal position.

The operation of the improved machine is substantially as follows: The shoe to be leveled is first jacked in the usual manner and the starting handle is then manipulated to oscillate the jack and cause the leveling roll to traverse over the shoe sole. As the roll and jack are moved to change the relative longitudinal position of the shoe and jack, the jack is tipped laterally by the operator to impart the desired curvature in cross section to the sole. The hand wheel 69 in the meantime has been adjusted to secure the proper frictional contact between the brake and roll and enable the roll to exert the proper rubbing action upon the shoe bottom. This rubbing action depends upon two factors; first the friction between

the brake and roll, and second, the friction between the roll and the surface of the sole. It is obvious that the friction between the roll and the surface of the sole will depend both upon the nature and character of the sole and the pressure of the roll thereon, and the amount of retardation of the roll may be varied by changing the pressure of the roll upon the work without altering the adjustment of the friction brake. Thus with a fixed adjustment of the brake, the roll may be caused to exert a rubbing action upon the sole when pressed against it lightly, and a rolling action when the pressure is increased. The pressure of the roll upon the work is conveniently controlled by a treadle and it may fairly be said that the mechanism for retarding the rotation of the roll acts in conjunction with the treadle to cause the roll to exert both a rubbing and rolling action upon the sole.

The nature and scope of the present invention having been indicated, and a machine embodying the various features thereof in their preferred form having been specifically described, what is claimed is:—

1. A leveling machine, having, in combination, a leveling roll, a shoe supporting jack, means for changing the relative longitudinal position of the roll and jack to cause the roll to traverse over the shank and ball portion of the shoe bottom and pass on to and off of the toe of the shoe, a stop, and means for positively moving the stop into an operative position to support the roll in passing on to and off of the shoe and for removing the stop to allow the roll to follow the contour of the sole during the entire leveling operation, substantially as described.

2. A leveling machine, having, in combination, a leveling roll, a supporting frame for the leveling roll, a movable jack for supporting a boot or shoe, a vertically movable stop for the supporting frame, a toggle connected to the lower portion of the stop, a spring normally tending to break the toggle and depress the stop, a rotary cam, and connections between the cam and toggle adapted to straighten the toggle and raise the stop, substantially as described.

3. A leveling machine, having, in combination, a shoe supporting jack, a leveling roll arranged to be rotated by frictional contact with the sole as the roll passes thereover, and friction means for retarding the rotation of the roll, substantially as described.

4. A leveling machine, having, in combination, a leveling roll, a jack for supporting a boot or shoe, means for changing the relative longitudinal position of the roll and jack, the leveling roll adapted to be rotated by frictional contact with the sole as the roll passes thereover, and means acting to

- partially retard the rotation of the roll to exert a rubbing action upon the sole, substantially as described.
5. A leveling machine, having, in combination, a leveling roll, means for vibrating the leveling roll, a movable jack for supporting a boot or shoe, means for moving the jack, the leveling roll adapted to be rotated by frictional contact with the sole of the boot or shoe as the roll passes thereover, and a friction device vibrating with the roll and adapted to bear upon the roll and retard its rotation to exert a rubbing action upon the sole, substantially as described.
10. 6. A leveling machine, having, in combination, a leveling roll, a movable jack for supporting a boot or shoe, friction means acting to retard the rotation of the roll to exert a rubbing action upon the sole, and means for varying the amount which the roll is retarded, substantially as described.
15. 7. A leveling machine, having, in combination, a leveling roll, a movable jack for supporting a boot or shoe, a friction brake yieldably pressed against the surface of the roll to exert a rubbing action upon the sole, and means for varying the pressure of the friction brake upon the roll, substantially as described.
20. 8. A leveling machine, having, in combination, a leveling roll, a movable jack for supporting a boot or shoe, slide bearings in which the roll is journaled, and a friction brake supported by the slide bearings and yieldably pressed against the surface of the roll, substantially as described.
25. 9. A leveling machine having, in combination, a leveling roll arranged to be rotated by frictional contact with the sole, a shoe supporting jack, means for retarding the rotation of the roll to exert a rubbing action upon the sole, and means under the

control of the operator for varying the retardation of the roll, substantially as described.

45

10. A leveling machine having, in combination, a leveling roll, means for vibrating the roll, a shoe supporting jack, means for changing the relative longitudinal position of the roll and jack, and friction means for 50 retarding the free rotation of the roll to exert a rubbing action upon the sole, substantially as described.

11. A leveling machine having, in combination, a leveling device, a shoe supporting 55 jack, means for changing the relative longitudinal position of the leveling device and jack, and mechanism for causing the leveling device to exert a rubbing action when pressed lightly upon the sole and a rolling 60 action when the pressure upon the sole is increased, substantially as described.

12. A leveling machine having, in combination, a leveling device, a shoe supporting 65 jack, means for changing the relative longitudinal position of the leveling device and jack, a treadle, and mechanism acting in conjunction with the treadle to cause the leveling device to exert either a rubbing or a rolling action upon the sole, substantially 70 as described.

13. A leveling machine comprising a roll, a supporting frame in which the roll is journaled, a friction pad slidably mounted in the frame and engaging with the periphery of the roll, and a spring bearing against the pad to yieldingly maintain it in engagement with the roll, substantially as described.
